UNITED STATES PATENT OFFICE.

LEWIS L. HEPBURN, OF NEW HAVEN, CONNECTICUT.

MAGAZINE-GUN.

SPECIFICATION forming part of Letters Patent No. 400,679, dated April 2, 1889.

Application filed January 12, 1889. Serial No. 296,129. (No model.)

To all whom it may concern:

Be it known that I, LEWIS L. HEPBURN, a citizen of the United States, residing at New Haven, in the county of New Haven and State of Connecticut, have invented certain new and useful Improvements in Magazine-Guns, of which the following is a specification.

This invention relates to magazine-guns; and the invention consists in certain features hereinafter described.

Figure 1 is a longitudinal vertical section of the breech portion containing the mechanism; Fig. 2, a transverse vertical section on the line $x\bar{x}$ of Fig. 1, and showing the breech-block detached. Fig. 3 is a top plan view of the carrier and a portion of its operating-lever. Figs. 4 and 6 are side elevations of the carrier with its operating dog or rocker and lever, the position of the parts being reversed from that shown in Fig. 1 to more clearly illustrate their mode of operation. Fig. 5 is a longitudinal transverse section on the line $w\bar{w}$ of Fig. 1 to show the extractor and ejector, and Fig. 7 is a similar sectional view to show how the rear end of the barrel is made to project into the cavity within the receiver and the cut in its lower wall.

This is an improvement on the gun for which Patent No. 371,455 was granted to me October 11, 1887, the reciprocating breech-block B and its locking-block D being constructed and arranged to be operated by the lever L L', the same as in that case, and which therefore need not be specially described in this case.

Instead of making the receiver or frame A with a slot or opening at the top, as in the former gun, and as is customary in this class of guns, I now make it in the side, as shown at I, Fig. 2, the breech-block, when at its forward position, as it must be when the gun is ready to fire, being so formed as to completely close this opening I, its outer surface coming flush with the side or face of the receiver, the same as in the former case it was made to come flush with the top of the receiver, and which is done by simply forming the breech-block with a projection on its side of the size and shape of the opening or slot I, in which it moves as the breech-block is moved to and fro to open and close the gun. The advantages of this construction are, first,

that rain, snow, &c., are less likely to get into the receiver, the cartridge-shell is thrown out laterally and away from the person holding the gun, and, finally, in case a cartridge-head should burst, the face is better protected from injury.

The next feature of my invention consists in extending the rear end of the barrel C farther back, so it shall enter the cavity in the receiver, as shown in Figs. 1, 2, and 7. The lower wall of this projecting portion of the barrel is cut away, as shown at a, Figs. 2 and 7, to permit the front end of the carrier E to pass, as otherwise it would be stopped at that point and would not raise the cartridge high enough to enter the bore of the barrel. As the front end of the cartridge when raised passes up through this cut on the lower side of the barrel, it will be held between the side walls of the projecting end, and will thus be prevented from rolling laterally off of the carrier, and will also be guided into the barrel with ease and certainty.

The carrier E is pivoted at its rear end in essentially the same position as before, but is differently constructed and operated. As shown in Figs. 1, 4, and 6, its front portion on which the cartridge rests is made in the form of a simple flat finger or plate of a width equal, or nearly so, to the width of the cavity between the side walls of the receiver, and with a vertical shoulder, r, against which the head of the cartridge rests when it is forced out of the magazine onto the carrier. As shown in Fig. 3, the rear portion of the carrier E is cut away along one side to permit the lever-arm L' to play freely to and fro to move the breech-block B. The front portion of the carrier is also cut away on its upper surface, as shown at v, Fig. 3, this cut being inclined both vertically and laterally, thereby leaving an inclined or slanting wall u at the left-hand side of the cut, and also giving an inclined surface to the part r. This is done to enable the cartridges to be fed or pushed through the opening in the side of the receiver into the magazine, and also to permit the carrier to rise slightly before the cartridge is fully out, the inclined position of the carrier causing the edge of its front portion to come partially opposite the lower edge of said opening. The opening in the receiver for the insertion

of the cartridges and its spring-door, being such as is common in this class of guns, is not shown. The carrier E in rear of its shoulder *r* is made much thicker vertically, and has a slot cut through it transversely, in which is pivoted a peculiarly-constructed dog or rocker, *o*, as shown in Figs. 1, 3, and 4, the form of the rocker being shown in Fig. 3 partly in dotted lines. This rocker *o* is pivoted in the slot in the carrier E by a vertical pin, *e*, near its rear end, as shown in Fig. 3, it being so pivoted or arranged that its front end can play freely back and forth sidewise in the slot. At its rear end it is provided with a laterally-projecting shoulder, *b*, and at its front end with another shoulder, *c*, and it is so pivoted in the slot that when it lies parallel with the body of the carrier these two shoulders both project laterally beyond the edge of the carrier, where the latter is cut away for the movement to and fro of the lever-arm *L'*, as clearly shown in Fig. 3. There is sufficient space between the right-hand side of the carrier and the adjoining wall of the receiver to permit the front end of the rocker *o* to swing back far enough to permit the lever *L'* to pass freely by the shoulder *c*, as shown by dotted lines in Fig. 3, the rocker being provided with a lip, *h*, at its front end, which serves as a stop to limit its movement in the opposite direction. The rear shoulder, *b*, of the rocker is provided with a flat face, against which the rear edge of lever *L'* strikes when thrown back, thereby swinging the rocker into position parallel with the carrier. The front shoulder or stud, *c*, is inclined or beveled on its front side, so that if it should not be back out of the way when the lever is moved backward the lever, acting on this incline, will shove it back out of the way of the lever. Its rear face is slightly rounded to enable it to slide freely up the inclined face of the lever, and is slightly undercut, so as to engage with the beveled face *m* of the lever and prevent it from slipping off or disengaging from the lever until the carrier has been raised to the proper height.

The beveled edge *m* of the lever is shown in Figs. 4 and 6, the position of the parts being reversed in these figures for that purpose. Just above the termination of the beveled portion it is made flat, and on the opposite side it is cut away or beveled in the opposite direction, as shown at *t*, Fig. 1. The result of this construction is that when the parts are secured in position, as shown in Fig. 1, the backward movement of the lever *L'* to the position shown by the dotted lines in Fig. 1 and in full lines in Fig. 6 brings the rear edge of the lever in contact with the shoulder *b*, and thereby swings the rocker into position parallel with the carrier, thus bringing the front stud, *c*, out in front of the lever *L'*, as shown in Fig. 6, when as the lever is moved forward its beveled edge *m* engages against the stud

c of the rocker *o*, and, owing to the inclined position of the lever, raises the carrier as the lever advances, the stud *c* sliding up along the face of the lever, until it comes opposite the beveled portion *t* on the side of the lever next to the rocker, when the lever is disengaged from the stud *c* by means of said incline or bevel *t*, and which as the lever passes by the stud throws the rocker back, when the carrier is free to drop by gravity. It will thus be seen that the carrier is both raised and lowered during the single forward movement of the lever-arm *L'*, and that when the lever is again thrown back to open the breech its rear edge striking against the stud *b* throws the rocker *o* into position ready for again raising the carrier as the lever-arm is again moved forward.

By examining Fig. 1 it will be seen that there is an eccentric shoulder, *w*, formed on the side of the lever-arm *L'*, where it will bear against the under side of the carrier E when the latter is down, or that will come in contact with the carrier as the lever is moved to open the breech and slightly raise the carrier, the object of which is to raise the front end of the carrier just enough to prevent a second cartridge from passing out of the magazine, the first one having already moved out onto the carrier far enough to permit the front end of the carrier to rise sufficiently to be in line with the lower edge of the head of the next cartridge. The carrier is provided with the usual lip on its under side, which, while the carrier is elevated, also covers the upper portion of the mouth of the magazine, as shown in dotted lines in Fig. 1, and thereby prevents the cartridges from coming out of the magazine while the carrier is raised.

The extractor-hook *e* is made with two spring-arms, as shown in Fig. 5, and is set in a longitudinal recess or hole bored in the front end of the breech-block *B*, in which it is secured at its rear end by a pin in such a manner as to avail of the elasticity of both of its arms, thereby securing a very elastic extractor, which is far less liable to break, especially when the metal is affected by extreme cold, and at the same time enabling the breech-block to be made solid on its exterior, and rendering the extractor less liable to be rendered inoperative by particles of sand or dirt getting under it, as is apt to be the case when a flat spring-hook is secured in a groove on the exterior face of the breech-block.

In order to expel the empty shell through the side opening, *I*, of the receiver as it is drawn out of the chamber, I secure in a groove in the opposite wall of the receiver a flat-spring ejector, *f*, as shown in Fig. 5. This, as shown, is provided near its front end with a projection, *i*, the front face of which stands at a right angle to its body and serves as a stop against which the shell strikes as it is drawn back, the rear face of this projection being

inclined to enable the breech-block to readily pass by it when moved forward. A small groove is cut in the side of the breech-block, in which the projection rests when the breech-block is shoved forward. It follows that when the breech-block is given a quick movement back the shell is stopped by coming in contact with the shoulder of the ejector, and as the latter is released from the pressure of the breech-block the instant the front end of the latter passes the projection *i* the ejector springs forward and throws the shell out through the opening *I* with the greatest accuracy and certainty.

15 By these several improvements I am enabled to produce a gun having but few parts, working with efficiency, and that is safer in case of defective cartridges.

I am aware that guns have before been made with a receiver having its top closed, and with an opening in its side, and also that a patent has been granted showing such a construction, and also a plate attached to the breech-block by a pin and arranged to slide 20 in grooves in the walls of said opening, and I disclaim such construction or arrangement of devices; but

What I do claim is—

1. The combination, in a gun, of the receiver 30 *A*, having a solid or unbroken wall at its top, with the longitudinal opening *I* in its side, and the reciprocating breech-block *B*, of the proper form transversely to fill the cavity between the walls of the receiver and the opening *I* in its side, substantially as shown and described.

2. The carrier *E*, having the rocker or dog *o* pivoted therein, said rocker or dog being provided with the shoulders *b* and *c*, constructed as described, and adapted to engage 40 and operate with the lever *L'*, as set forth.

3. In combination with the receiver *A*, having an opening, *I*, in its side, and its top wall closed or unbroken, the barrel *C*, having its rear end projected backward into the cavity 45 of the receiver, and having a notch or recess, *a*, cut in its under wall only, substantially as and for the purpose set forth.

4. In combination with the pivoted carrier *E*, the pivoted lever *L*, provided with an eccentric, *w*, adapted to come in contact with the under side of the carrier as the lever is moved to open the breech, and elevate the front end of the carrier to a point just above the lower wall of the magazine-tube, and 55 thereby prevent the cartridge from prematurely passing out of the magazine, as set forth.

5. The flat-spring ejector *f*, provided with the projection *i*, said projection being provided with a right-angled face at its front and an inclined or beveled face at its rear side, the same being secured in a recess formed in the inner wall of the receiver, substantially as shown and described.

In witness whereof I hereunto set my hand in the presence of two witnesses.

LEWIS L. HEPBURN.
